Int. Cl. D3—02

U.S. Cl. D87—2 R

FIG. 1.

FIG. 2.

FIG. 3.

FIG. 4.

FIG. 1 is an upper perspective view of a purse organizer showing my new design, the four containers being identical and the back of each being plain;

FIG. 2 is a side elevational view thereof;

FIG. 3 is an end elevational view thereof; and

FIG. 4 is a fragmentary sectional view thereof on an enlarged scale, taken on line 4—4 of FIG. 2.

The drawing has been lined to indicate transparency.

The organizer is symmetrical about central transverse and longitudinal vertical planes.

I claim:

The ornamental design for a purse organizer or the like, substantially as shown and described.
